UNITED STATES PATENT OFFICE.

ELI SPITLER, OF MOSCOW, IDAHO.

PROPELLING MECHANISM.

1,332,475.

Specification of Letters Patent.

Patented Mar. 2, 1920.

Application filed May 17, 1918. Serial No. 235,128.

To all whom it may concern:

Be it known that I, ELI SPITLER, a citizen of the United States, residing at Moscow, in the county of Lotah and State of Idaho, have invented certain new and useful Improvements in Propelling Mechanisms, of which the following is a specification.

This invention relates generally to propelling mechanism, and is adapted particularly for use upon ships.

The primary object of the invention is to provide means of an improved character whereby the propeller itself may be actuated so as to drive the vessel at different speeds without changing the speed of rotation of the propeller shaft.

A further object of the invention is to provide adjustable propeller blades of improved construction which may be readily actuated to instantly change the angle of the blade whereby the speed of the vessel will be changed and which means is so constructed and assembled as to minimize the opportunity for wear or breakage.

With these objects in view, together with others which will appear as the description proceeds, the invention resides in the novel formation, combination and arrangement of parts, all as will be described more fully hereinafter, illustrated in the drawings, and particularly pointed out in the claim.

In the drawings:—

Figure 1 is a side elevation of the improved propeller mechanism constructed in accordance with the invention,

Fig. 2 is a top plan view of the means for controlling the degree of angularity of the propeller blades,

Fig. 3 is a longitudinal sectional view taken through the propeller blade supporting housing, and

Fig. 4 is an end view of the propeller housing with the cap removed therefrom, and illustrating the mechanism by which the movements of the blades are controlled.

Referring now more particularly to the drawings, 5 represents posts or blocks for the support of the propeller shaft, bearings 6 of conventional form being arranged at the upper end thereof to rotatably support the said shaft.

The propeller shaft in the present instance is hollow, and is indicated at 7. This shaft is provided at its inner end with a pulley 8 to be coupled with the engine or other power mechanism upon the boat, whereby

rotary movement may be developed in the propeller shaft. The outer end of the shaft is provided with a double-conical head including a substantially conical housing section indicated at 9, over the end of which a similarly formed cap 10 is engaged. The hollow section 9 and cap 10 have their base portions of substantially the same diameter and these base portions fit together and are held properly assembled by the securing straps 11. By so arranging the housing, it is obvious that the cap may be readily removed when it is required to repair or inspect the mechanism which is to be located within the housing.

Rotatably mounted in bearings 12, at the outer end of the section 9 and disposed transversely thereof, are the inner ends or shanks of propeller blades 13. The blades at the opposite sides of the housing section are in alinement with each other and are disposed at right angles to the length of the driving shaft 7. The inner ends of said shanks are provided with crank arms 14, to the ends of which links 15 are connected. These links at their inner ends are pivotally connected to a rod 16 which is disposed within and extends throughout the length of the hollow shaft 7.

The inner end of the rod 16 protrudes beyond the corresponding end of the hollow shaft 7, and is rotatably mounted in a transverse bar 17. This bar 17 has secured to its ends the extremities of a U-shaped bail 18, the latter being rotatably mounted at its bend in a bearing 19 arranged adjacent the upper end of a lever 20. The lever 20 is pivoted at its lower end as at 21 within the vessel with which the device is used, and has pivoted at its other extremity a handle 22 provided with a series of spaced notches 23 adapted to engage over a plate 24 secured to the upper end of a stanchion or post 25. By so constructing the device, it is obvious that the throw of the lever 20 may be controlled by the handle. The lever 20 is held positively locked in any of its positions of adjustment by engagement of the plate within the notches on the handle.

The drawing illustrates the improvements independently of a vessel, but it will be understood that the device is to be located at the proper place within the vessel so that housing at the outer end of the propeller shaft will protrude beyond the vessel and at the proper distance below the surface of the

water. A belt from the source of motor power may be passed over the pulley 8, and the mechanism is ready for operation. The shaft 7 is driven at a steady speed, and when it is desired to vary the speed of the vessel, the rod 16 is moved inwardly or outwardly of the hollow shaft 7. This sliding movement of the rod causes the blades 13 to be rotated within the supporting blocks or bearings 12 whereupon the degree of angularity of the blades will be changed. If desired, the apparatus may be so operated that the propellers will be disposed in a single plane, whereupon the rotation of the device will not operate to drive the vessel in either direction. By working the rod 16 longitudinally of the propeller shaft, the angularity of the blades may be changed so as to offer a relatively great resisting surface to the water whereupon the vessel will be driven at good speed. When it is desired to reverse the direction of travel of the vessel, the rod 16 is moved inwardly of the casing until the outer extremities of the links 15 extend beyond the inner ends of the blades 13 whereupon the blades will be disposed at such angle as to deliver pulling power upon the supporting or driving shaft 7. It is obvious, therefore, that the direction of rotation of the shaft 7 need not be changed to drive the vessel in either direction.

The foregoing description and the draw-

ings have reference to what may be considered the preferred or approved form of my invention. It is to be understood that I may make such changes in construction and arrangement and combination of parts, materials, dimensions, etc., as may prove expedient and fall within the scope of the appended claim.

Having thus described the invention, what I claim as new and desire to secure by Letters Patent, is:—

In a device of the class described, the combination of a hollow propeller shaft having a double conical head upon its outer end, thereby forming a conical housing and a conical cap, cylindrical flanges provided upon the enlarged end of said housing and said cap so that the flange of said cap will inclose the flange of said housing, straps carried by said cap and connected to said housing for holding the head assembled, said housing having bearings upon its outer end contiguous to said cap, blades having shanks carried by said bearing, means carried within said shaft and head for turning said shanks to adjust the pitch of said blades.

In testimony whereof I affix my signature in presence of two witnesses.

ELI SPITLER.
